UNITED STATES PATENT OFFICE

HENRY J. BLAKESLEE, OF MARLBORO, CONNECTICUT

SAFETY MEANS FOR ELECTRIC CIRCUITS

Continuation of application Serial No. 219,917, filed September 16, 1927. This application filed October 21, 1929. Serial No. 401,271.

This invention relates to means for automatically opening, in case of accident to the load lines, the supply lines of electric light, heat and power circuits.

5 The object of this invention is to provide simple means which will instantly open the supply line of a circuit whenever the load line becomes broken, and will retain the supply line open until the break is repaired and the 10 conditions in the load line are restored to normal.

This object is attained by connecting a trip switch in the circuit of a motor which is connected to operate a switch in the supply line, 15 and arranging means subject to the relative conditions of voltage and current in the load line which will cause the trip switch to shift the circuit connections so that the motor will open the supply line switch whenever the 20 load circuit is broken, and will retain the supply line open until the load line break is repaired and the trip switch is closed.

The invention is adaptable to circuits that are controlled by time switches, and consequently it is described herein in connection therewith, although applicable to circuits controlled by other means.

This application is a continuation of my application Serial No. 219,917, filed Sept. 16, 30 1927.

Fig. 1 shows diagrammatically the connections of a time switch arrangement in working relation, that is, when the main switch is closed and the load circuit is in normal condition.

Fig. 2 is a similar view showing the elements with the load line broken, the main switch open and the motor circuit open so that while the time mechanism will run as usual the motor circuit will remain open and the motor will not turn the main switch until the trip switch of the safety means is again closed.

The time piece 1 is a clock of a common 45 type used in time switch installations and it has the usual adjustable trips 2 which during their rotations, according to the positions in which they are set, engage with a finger 3 that is connected with an escape- 50 ment anchor 4. A spring 5 is arranged to

normally keep the end of the finger in the path of the trips. The ends of the escape- 55 ment anchor are designed to engage the arms of an escape wheel 6 which may be rotated by a spring 7. As the finger is depressed by a trip and subsequently rises, the anchor allows the escape wheel to be turned 90°, after the manner of common anchor escapements. The escape wheel is fastened on a spindle 8 on which are fastened a conducting disk 9 60 and two segmental conductors 10 and 11, which disk and segmental conductors comprise the clock controlled switching means. This disk and these segmental conductors may be electrically connected through the 65 spindle or by a conductor 12 and the segments are arranged at 90° with relation to each other so that first one segmental conductor will make contact with its brush 13 and the other segmental conductor will make contact with its brush 14 as these parts are turned by the rotary movements of the escape 70 wheel. The brush 15 is always in conducting engagement with the disk 9.

The double pole main switch 16 which 75 completes and opens the supply lines 17, 18 is fastened to a spindle 19. Fastened on this spindle is a sprocket wheel 20 which is connected by a chain 21 with a sprocket pinion 22 on the shaft of a motor 23. Also fastened 80 on and rotating with this spindle and the main switch there is a conducting disk 24 and segmental conductors 25 and 26. This disk and these segmental conductors may be electrically connected through the shaft or by 85 a conductor 27, and they comprise the switch which is turned with the main switch by the motor. In this case the segmental conductors are arranged at 90° with relation to each other and to the segmental conductors of 90 the clock controlled switch. A brush 28 bears on the disk 24, a brush 29 is adapted to engage segmental conductor 25, and a brush 30 is arranged to engage segmental conductor 26. The brushes 14 and 30 are electrically connected by a conductor 31 and the brushes 13 and 29 are electrically connected by a conductor 32. The brush 28 is electrically connected by a conductor 33 with one 95 terminal of the secondary of a transformer 100

34 that is connected across the supply lines 17 and 18. The other terminal of the secondary of this transformer is connected by a conductor 35 with a brush 36 of the motor. The other brush 37 of the motor is connected by a conductor 38 with a trip lever 39 which is normally held in position to close the circuit between the motor and the disk 9 through the conductor 40 that is connected with the brush 15 of the disk 9. This lever is retained with this part of the circuit closed by a latch 41 and a spring 42, Fig. 1. A spring 43 is arranged to pull the trip lever, when the latch is lifted so as to open the circuit between the brush 15 and the motor and close the circuit between the brush 13 and the motor, Fig. 2.

For the purpose of lifting the latch and releasing the trip lever, the apparatus illustrated has a balanced solenoid with coils 44 and 45 encircling cores 46 and 47 which are connected to a rocker 48, the core 46 being adapted to engage the latch. The coil 44 is connected with the load side of the main switch so as to be responsive to the voltage therein, which may be affected by connecting the ends of the coil 44 with the terminals of the secondary of a transformer 49 which is connected across the line, and the coil 45 is connected with the load line so as to be responsive to the current therein, which may be affected by connecting the ends of the coil 45 with the terminals of the secondary of a transformer 50 in series in the load line, which load line is illustrated as receiving its current from the transformer 51. With the circuits in normal working condition the solenoid cores are balanced as the effect of the current in each coil will be the same. Should, however, the load circuit become broken through any accident no current will flow through the coil 45 but current will still continue to flow through the coil 44.

This eliminates the solenoid balance so that the core 46 will be projected and cause the latch to release the trip lever, which will then close the motor circuit. The motor will then operate to open the main switch, the turning of which will again open the motor circuit. The main and motor circuits will remain open until the break in the load circuit is repaired, the trip switch lever is re-engaged with the latch, and the current in the solenoid coils is again balanced.

In normal use the safety elements may be placed on poles or in manholes or at substations for the purpose of automatically opening and keeping open the supply circuit whenever any break occurs in the load circuit. The motor circuit is closed by two switches, one, comprising the disk 9 and the segmental conductors 10 and 11, illustrated as operated from the clock, and the other comprising the disk 24 and segmental conductors 25 and 26, operated from the motor,

and the main switch in the supply line is thrown positively by the motor. When the load circuit is open the clock can go on indefinitely for under these conditions the motor circuit is open and the main switch remains open. The clock through the connections illustrated automatically causes the main switch first to close and then to open according to the engagement of the trips on the time piece with the finger connected to the escapement anchor.

The clock circuit starts the motor and the motor drives the main switch both to open and close the supply line, when the load circuit is in working condition. On the completion of each movement of the main switch the clock-motor circuit is opened.

The apparatus, as stated, is illustrated diagrammatically for the purpose of showing the relative arrangement of the elements and their connections, but it is to be understood that the parts may be assembled and enclosed in a suitable casing, as will be apparent to those skilled in this art.

The invention claimed is:

1. Safety means for electric circuits comprising, a transformer having primary and secondary windings, a motor, a main switch mechanically connected to and operated by the motor and adapted to connect and disconnect said primary winding with an electrical source, a load circuit connected to said secondary winding, an electromagnetically actuated switch having two windings, one winding adapted to be energized when said primary is energized, the other winding adapted to be energized when current flows in said load circuit, and conductors connecting the electromagnetically operated switch with the motor and with an electrical source, whereby when the current in the load circuit is interrupted the electromagnetic switch will act to so connect said conductors that the motor will cause the main switch to disconnect the primary coil of the transformer from the electrical source.

2. Safety means for electric circuits comprising a transformer having primary and secondary windings, a motor, a main switch mechanically connected and operated by the motor and adapted to connect and disconnect said primary winding with an electrical source, a load circuit connected to said secondary winding, an electromagnetically actuated switch having two windings, one winding being connected with the secondary of a transformer adapted to be connected across the primary circuit, the other winding being connected with the secondary of a transformer adapted to be connected in the secondary circuit, and conductors connecting said electromagnetically operated switch with the motor and with an electrical source, whereby when the current in the load circuit is interrupted the electromagnetically oper-

ated switch will act to so connect said conductors that the motor will cause the main switch to disconnect the primary coil of the transformer from the electrical source.

5. Safety means for electric circuits comprising a motor, a main switch mechanically connected to and operated by the motor and adapted to connect and disconnect an electrical source with a load circuit, an electro-magnetically actuated switch having two windings, one winding having an electrical connection across the load side of the main switch, and the other winding having an electrical connection in series with the load circuit, and conductors connecting the electro-magnetically operated switch with the motor and with an electrical source, whereby when the current in the load circuit is interrupted the electromagnetic switch will act to so connect said conductors that the motor will cause the main switch to disconnect the load circuit from the electrical source.
6. Safety means for electric circuits comprising a motor, a main switch mechanically connected to and operated by the motor and adapted to connect and disconnect an electrical source with a load circuit, an electro-magnetically actuated switch having two windings, one winding being connected with a transformer connected across the load side of the main switch, and the other winding connected with a transformer connected in series with the load circuit, and conductors connecting said electro-magnetically operated switch with the motor and with an electrical source, whereby when the current in the load circuit is interrupted the electromagnetic switch will act to so connect said conductors that the motor will cause the main switch to disconnect the load circuit from the electrical source.
7. Safety means for electric circuits comprising a main switch connected between a current source and a load, a motor for operating the main switch, switching means operated with the main switch, auxiliary switching means and means for operating the same, conductors electrically connecting the second mentioned switching means with the first mentioned switching means and with the motor, a trip switch, conductors connecting the trip switch with the second mentioned switching means and with the motor, and means electrically associated with the load circuit for controlling the trip switch, whereby when the load circuit is closed the motor circuit will be closed through the trip switch and the motor circuit will be controlled by the second mentioned switching means, and when the load circuit is open the trip switch will close the motor circuit so that the motor will open the main switch.
8. Safety means for electric circuits comprising switching means and means for operating the same, a main switch connected between a current source and a load, a motor for operating the main switch, switching means operated with the main switch, conductors electrically connecting the first mentioned switching means with the second mentioned switching means and with the motor, a trip switch, conductors connecting the trip switch with the first mentioned switching means and with the motor, and a balanced solenoid associated with and controlled from the load circuit and controlling the trip switch, whereby when the load circuit is closed the solenoid is balanced and will retain the trip switch in normal position, and when the load circuit is opened the solenoid is unbalanced and the trip switch will shift and close the motor circuit so that the motor will open the main switch.
9. Safety means for electric circuits comprising switching means and means for operating the same, a main switch connected between a source of current and a load, a motor for mechanically operating the main switch, switching means operated with the main switch, conductors electrically connecting the first mentioned switching means with the second mentioned switching means and with the motor, a trip switch, conductors connecting the trip switch with both of said switching means and with the motor, and electromagnetic means electrically associated with the load circuit for controlling the trip switch, said means being responsive to change from

70 circuit, and normally closed, and a balanced solenoid responsive to change from the normal relations of the voltage supplied to the load circuit and the current in the load circuit, for releasing the trip switch and allowing it to open the normal circuit and close a circuit through the motor which will cause the motor to open the main switch.

75 10. Safety means for electric circuits comprising a main switch connected between a current source and a load, a motor for operating the main switch, switching means operated with the main switch, auxiliary switching means and means for operating the same, conductors electrically connecting the second mentioned switching means with the first mentioned switching means and with the motor, a trip switch, conductors connecting the trip switch with the second mentioned switching means and with the motor, and means electrically associated with the load circuit for controlling the trip switch, whereby when the load circuit is closed the motor circuit will be closed through the trip switch and the motor circuit will be controlled by the second mentioned switching means, and when the load circuit is open the trip switch will close the motor circuit so that the motor will open the main switch.

80 11. Safety means for electric circuits comprising switching means and means for operating the same, a main switch connected between a current source and a load, a motor for operating the main switch, switching means operated with the main switch, conductors electrically connecting the first mentioned switching means with the second mentioned switching means and with the motor, a trip switch, conductors connecting the trip switch with the first mentioned switching means and with the motor, and a balanced solenoid associated with and controlled from the load circuit and controlling the trip switch, whereby when the load circuit is closed the solenoid is balanced and will retain the trip switch in normal position, and when the load circuit is opened the solenoid is unbalanced and the trip switch will shift and close the motor circuit so that the motor will open the main switch.

85 12. Safety means for electric circuits comprising switching means and means for operating the same, a main switch connected between a source of current and a load, a motor for mechanically operating the main switch, switching means operated with the main switch, conductors electrically connecting the first mentioned switching means with the second mentioned switching means and with the motor, a trip switch, conductors connecting the trip switch with both of said switching means and with the motor, and electromagnetic means electrically associated with the load circuit for controlling the trip switch, said means being responsive to change from

115

120

the normal relations of the voltage supplied to the load circuit and the current in said load circuit and when the load circuit is open will cause the trip switch to close the motor circuit so that the motor will open the main switch.

10. Safety means for electric circuits comprising a motor, a main switch mechanically operated by said motor and adapted to connect and disconnect a load circuit to an electrical source, switching means associated with said motor for normally closing and opening said main switch, switching means also associated with said motor and responsive to change from the normal relations of the voltage supplied to the load circuit and the current in said load circuit, and conductors interconnecting said switching means and said motor whereby when the current in the load circuit is interrupted said switching means will so connect said conductors that the motor will cause said main switch to open.

11. Safety means for electric circuits comprising a motor, a main switch mechanically operated by said motor and adapted to connect and disconnect a load circuit to an electrical source, switching means associated with said motor for normally closing and opening said main switch, electromagnetic switching means also associated with said motor and responsive to change from the normal relations of the voltage supplied to the load circuit and the current in said load circuit, and conductors interconnecting said switching means and said motor whereby when the current in the load circuit is interrupted said switching means will so connect said conductors that the motor will cause said main switch to open.

12. Safety means for electric circuits comprising a main switch connected between a source of current and a load, a motor for mechanically operating the main switch, switching means operated with the main switch, auxiliary switching means, conductors electrically connecting said switching means, a trip switch, conductors connecting the trip switch with said switching means and with the motor, and normally balanced electromagnetic means electrically associated with the load circuit for controlling the trip switch, said magnetic means being balanced when the load circuit is closed, and unbalanced when the load circuit is open so that the trip switch will close the motor circuit and the motor will open the main switch.

HENRY J. BLAKESLEE.
